Inventor,

Jesse Bright,

By his Attorney,

Chas. C. Ladd.

UNITED STATES PATENT OFFICE.

JESSE BRIGHT, OF LEWISBURG, WEST VIRGINIA.

FENCE.

SPECIFICATION forming part of Letters Patent No. 388,338, dated August 21, 1888.

Application filed June 2, 1888. Serial No. 275,881. (No model.)

To all whom it may concern:

Be it known that I, JESSE BRIGHT, a citizen of the United States, residing at Lewisburg, in the county of Greenbrier and State 5 of West Virginia, have invented a new and useful Improvement in Fences, of which the following is a specification.

My invention relates to improvements in Fences; and it has for its object to provide 10 a simple, cheap, strong, and durable structure, wherein the points which are liable to be subjected to the greatest strains are suitably strengthened.

The invention consists in a certain novel 15 construction and arrangement of device fully set forth hereinafter in connection with the accompanying drawings, wherein—

Figure 1 is a perspective view. Fig. 2 is a transverse vertical sectional view.

Referring to the drawings, A designates the 20 crossed stakes or posts, which are set in the ground at their lower ends and intersect each other at about half their height, and the said intersection is bound by the tie-wire a, after 25 which the end of the intermediate panel-rail, B, is rested in the upper angle formed by the stakes. The outer crossed stakes, C C, are now arranged, respectively, parallel with the rails A and connected at their upper intersecting ends by the tie-wire d, the said outer stakes being 30 connected to the inner stakes at their points 70 of intersection by the tie-wires c c, in combination with the upper or rider rail arranged in the angle between the upper ends of the outer stakes, the intermediate rail arranged in the upper angle formed by the intersection 75 of the inner stakes, and the lower rails, E E, arranged between the adjacent sides of the parallel stakes and bearing on the tie-wires e e, which connect the said stakes, substantially as specified.

40

45

50

arranged in the spaces between the adjacent sides of the stakes, so that the strain upon one of the rails is distributed and borne by a number of tie-wires. The stakes intersect at four points, and being tied at all of the said 55 points they are rigidly connected, so that the four stakes act as a single post and mutually support each other. The lower ends of the outer stakes may be arranged in the ground; but I prefer to simply extend them to the surface of the ground, as shown in the drawings.

Having thus described the invention, I claim—

1. In a fence, the inner crossed stakes, A A, connected at their intersection by a suitable 65 tie-wire, a, the outer crossed stakes, C C, arranged, respectively, parallel with the rails A and connected at their upper intersecting ends by the tie-wire d, the said outer stakes being connected to the inner stakes at their points 70 of intersection by the tie-wires c c, in combination with the upper or rider rail arranged in the angle between the upper ends of the outer stakes, the intermediate rail arranged in the upper angle formed by the intersection 75 of the inner stakes, and the lower rails, E E, arranged between the adjacent sides of the parallel stakes and bearing on the tie-wires e e, which connect the said stakes, substantially as specified.

2. In a fence, the inner and outer crossed stakes, A A and C C, respectively, connected at their intersections by suitable tie-wires, and the upper and intermediate rails, D and B, respectively arranged in the angles formed by 85 the intersections of the said rails A A and C C, in combination with the parallel horizontal rails E E, arranged side by side below the intermediate rails and secured at their ends between the adjacent lower ends of the said 90 stakes, whereby the bottom of the fence is fortified against the attacks of confined animals, substantially as specified.

In testimony that I claim the foregoing as my own I have hereto affixed my signature in presence of two witnesses.

JESSE BRIGHT.
